UNITED STATES PATENT OFFICE

148,510

DESIGN FOR A PLATE OR THE LIKE

Ching-Chih Yee, New York, N. Y., assignor to Castleton China, Incorporated, New York,
N. Y., a corporation of New York

Application February 21, 1947, Serial No. 137,067

Term of patent 14 years

(Cl. D44—15)

To all whom it may concern:

Be it known that I, Ching-Chih Yee, a citizen of China, residing at New York, in the county of New York and State of New York, have invented a new, original, and ornamental Design for a Plate or the like, of which the following is a specification, reference being had to the accompanying drawing, forming part thereof.

The figure is a plan view of a plate showing my new design.

I claim:

The ornamental design for a plate or the like, as shown.

CHING-CHIH YEE.
